UNITED STATES PATENT OFFICE.

CHARLES W. DAKE, OF CHICAGO, ILLINOIS.

TURBO BLOWER.

Application filed April 5, 1926. Serial No. 99,780.

My invention relates to improvements in 5 turbo blowers and has for one object to provide a new and improved form of steam turbine driven air or exhaust gas blower combination. My invention is exemplified in a 10 turbo blower adapted to be used in locomotive practice for providing a forced draft but it will be obvious that the combination and arrangement might be used in any condition where steam power is available and it 15 is desirable to use it to drive a fan or blower. Other objects will appear from time to time throughout the specification and claims.

My invention is illustrated more or less 20 diagrammatically in the accompanying drawings, wherein—

Figure 1 is a side elevation of the turbo- 25 blower;

Figure 2 is a plan view;

Figure 3 is a section along the line 3—3 30 of Figure 2;

Figure 4 is a section along the line 4—4 35 of Figure 3;

Figure 5 is a section along the line 5—5 40 of Figure 3.

Like parts are indicated by like characters 45 throughout the specification and drawings.

A is a bed plate or base. It may be and in 50 this case is a part of the wall of a locomotive boiler. A¹ is the blower housing. It is flanged at A² and held by means of the studs A³ in place on the bed plate A. In this case the bed plate is apertured as at A⁴ to permit products of combustion from the furnace to 55 pass up through the aperture A⁵ into the body of the blower housing. The upper extremity of the housing A¹ is interiorly flanged as at A⁶ and exteriorly flanged as at A⁷. A⁸ is the exhaust passage and integral with the housing A¹ through which 60 the burnt gases are discharged into the pipe A⁹. It will be noted that this housing is gradually expanded from the point A¹⁰ around the periphery of the housing to the 65 large discharge passage A⁸ in the usual manner.

Superposed on the fan housing A¹ is the 70 turbine housing B, flanged at B¹ to engage the housing A¹ adapted to be held thereon by means of the studs B². This housing is open at the bottom in register with the opening through the flange A⁶ and closed at the top by a flat wall B³ with a centrally disposed boss B⁴ which boss terminates in an 75 interiorly and outwardly extending sleeve B⁵. B⁶ is the steam supply pipe discharging

into the turbine housing. B⁷ is the exhaust steam discharge pipe leading tangentially therefrom and leading to the exhaust main B⁸.

C is a stub bearing shaft held in place rigidly in the sleeve B⁵ by means of the castellated nut C¹, the shoulder C² and the key C³. This stub shaft extends down into the space enclosed by both the turbine housing and the blower housing. It is flanged at C⁴ to engage the large upper ball bearing C⁵ and shouldered at C⁶ to engage the lower smaller ball bearing C⁷. The nut C⁸ holds the lower ball bearing in place against the shoulder at C⁹ at the lower end of the stub shaft. C⁹ is a bearing housing sleeve shouldered at its inner and outer ends as indicated to engage respectively the bearings C⁵ and C⁷. It is closed at its lower end by the cap C¹⁰, there being clearance between the cap C¹⁰ and the bearing C⁶ so that if the distance between the upper and lower shoulders C⁹ should increase by expansion the lower shoulder might pull away from the bearing C⁷ without interfering with the continued operation of the parts.

The member C⁹ is flanged at D to substantially close the opening in the boss B⁴. This flange terminates in a mitered surface 85 in opposition to a mitered surface D¹ on the flange D² interiorly disposed about the periphery of the boss B⁴. D³ is a packing flange encircling the shaft C provided with a packing ring D⁴. This flange has a shoulder D⁵ adapted to engage the races of the ball bearing C⁵, and is held in place by means of the cap screws D⁶. The bearing C⁵ is free to move upwardly along the shaft C away from the shoulder C⁹ so that if expansion of the member C⁹ takes place the parts may rise above the shoulder C⁹ without harm being done. The space within the member C⁹ between it and the shaft C and enclosing the two bearings is adapted to be 90 filled with lubricant to lubricate the ball bearings.

The fan or blower runner comprises a 95 conical part E, the apex of the cone being in line with the shaft C prolonged and being pointed down toward the incoming gases. The periphery of the runner E is shouldered as at E¹ to come into close engagement though not actual contact with the flange A⁶ and substantially close the opening through the flange A⁶ thus separating the steam and the gas chambers in the two hous- 100 105 110

ings. There is a flange extending beyond and overhanging the flange A⁶ as at E² to carry the turbine rotor buckets E³ which are held in place by means of a shroud E⁴ and rivets E⁵ extending through the flange E² through each bucket and through the shroud. Extending downwardly from the runner E are a plurality of blower buckets E⁶. These buckets are riveted to the under- 10 side of the runner and riveted at their lower extremity to a shroud E⁷ whereby they form a cage open at the bottom of the intake end of the blower adapted to discharge radially into the space between the rotor and the 15 housing in the usual manner.

E⁸ is a bearing flange on the inner upper side of the runner adapted to engage a cylindrical bearing surface on the outside of the member C⁹. Extending upwardly from this bearing surface is a conical sleeve E⁹ which terminates at its upper end in a flange E¹⁰ adapted to be held onto the flange D by means of cap screws E¹¹ and which also has a bearing surface E¹² adapted to engage 25 a corresponding bearing surface on the upper end of the member C⁹ whereby the rotor or runner and its associated parts may be removably mounted on the bearing hub whereby a dead air space may be interposed 30 between the bearing hub and the walls of the runner heated in part by the exhaust or burnt gas from the engine and in part by the steam itself.

The steam pipe B⁶ discharges into a steam 35 chest F disposed in the wall of the turbine housing. This steam chest F has at either end a downwardly extended branch F¹. Each of the branches communicates with a steam pocket F² closed by a cap F³ and in line with a removable steam nozzle F⁴ which 40 nozzle expands the steam and discharges it against the turbine buckets in the usual manner, the steam being discharged radially. Opposed to the inner periphery of the 45 turbine wheel and opposed nozzles F⁴ are two pairs of return passages F⁵ F⁶ which gather the steam after it has passed through the buckets and discharge it again into the buckets at a point further along the wheel. 50 These return passages are contained within return passage blocks F⁷ mounted on brackets F⁸ bolted to the underside of the top of the housing as at F⁹. The steam after being discharged by the return passages against 55 the buckets passes out of the buckets outside the turbine wheel and thence to the exhaust as indicated. Since there is a free flow of exhaust or steam out of the housing and since there is a free flow of gas out of 60 the blower housing, it is not necessary to have a gas or steam tight wall interposed between the two housings. No particular harm would be done if there was some mixture of the steam and the burnt gases be- 65 cause in either event they are sent out to

the atmosphere or to the exhaust just as rapidly as possible.

I claim:

1. In a turbo blower having turbine and blower housings, a rotor interposed between and forming a partition between them, and a bearing support for the rotor mounted on the wall of the turbine housing, extending therethrough and into but out of contact with the blower housing. 75

2. In a turbo blower having turbine and blower housings, a rotor interposed between and forming a partition between them, and a bearing support for the rotor mounted on the wall of the turbine housing, extending therethrough and into but out of contact with the blower housing, the rotor being removably mounted on the bearing support. 80

3. In a turbo blower having turbine and blower housings, a rotor interposed between and forming a partition between them, and a bearing support for the rotor mounted on the wall of the turbine housing, extending through and into but out of contact with the blower housing, the rotor being removably mounted on the bearing support, there being a dead air space between the rotor and the bearing support. 85

4. A bearing for turbines and the like comprising a rigidly mounted stub shaft, a pair of self-contained bearing members carried thereby, a sleeve mounted on the members enclosing them and free to rotate with them on the shaft, the sleeve being closed at one end and packing means interposed at the other end surrounding the shaft to enclose the sleeve the bearing members being each removable as a unit from the sleeve and from the shaft. 95

5. A bearing for turbines and the like comprising a rigidly mounted stub shaft, a pair of self-contained bearing members carried thereby, a sleeve mounted on the members enclosing them and free to rotate with them on the shaft, the sleeve being closed at one end and packing means interposed at the other end surrounding the shaft to enclose the sleeve, a rotor comprising a rotating plate and a sleeve adapted to surround the bearing sleeve and be removably mounted thereon the bearing members being each removable as a unit from the sleeve and from the shaft. 105

6. A bearing for turbines and the like comprising a rigidly mounted stub shaft, a pair of self-contained bearing members carried thereby, a sleeve mounted on the members enclosing them and free to rotate with them on the shaft, the sleeve being closed at one end and packing means interposed at the other end surrounding the shaft to enclose the sleeve, a rotor comprising a rotating plate and a sleeve adapted to surround the bearing sleeve and be removably mounted thereon, and a dead air space interposed be- 110

tween the two sleeves the bearing members being each removable as a unit from the sleeve and from the shaft.

7. In a turbine, a housing, a stub end shaft rigidly mounted on the end thereof and projecting into the housing, a bearing on the end of the shaft, the inner race of which is rigidly positioned thereon, a bearing intermediate the ends of the shaft, the inner race of which is free to move away from the first bearing, the shaft being flanged to prevent movement of the races toward said bearing, a sleeve shouldered to engage the adjacent sides of the two bearings, the sleeve being free to move upwardly away from the upper bearing and means for holding the sleeve rigidly with respect to the outer race of the upper bearing.
8. In a turbine, a housing, a stub end shaft rigidly mounted on the end thereof and projecting into the housing, a bearing on the end of the shaft, the inner race of which is rigidly positioned thereon, a bearing intermediate the ends of the shaft, the inner race of which is free to move away from the first bearing, the shaft being flanged to prevent movement of the races toward said bearing, a sleeve shouldered to engage the adjacent sides of the two bearings, the sleeve being free to move upwardly away from the upper bearing and means for holding the sleeve rigidly with respect to the outer race of the upper bearing.
9. In a turbine, a housing, a stub end shaft rigidly mounted on the end thereof and projecting into the housing, a bearing on the end of the shaft, the inner race of which is rigidly positioned thereon, a bearing intermediate the ends of the shaft, the inner race of which is free to move away

from the first bearing, the shaft being flanged to prevent movement of the races toward said bearing, a sleeve shouldered to engage the adjacent sides of the two bearings, the sleeve being free to move upwardly away from the upper bearing and means for holding the sleeve rigidly with respect to the outer race of the upper bearing, a cap closing the sleeve at its lower end, and overlying the end of the shaft, a packing disc encircling the shaft, closing the upper end of the sleeve and seated rigidly against the upper bearing and a packing ring interposed between the disc and the shaft, a turbo blower rotor comprising a conical runner plate enclosing the lower end of the bearing sleeve, the sleeve extending upwardly from said plate and encircling the bearing sleeve and removably attached thereto at its upper end, the periphery of the runner being located in a plane intermediate the two bearings.

10. In a turbine, a shaft, a sleeve mounted for rotation upon and enclosing one end of the shaft, bearings interposed between the sleeve and the shaft, a rotor removably mounted on the sleeve comprising a conical plate, a sleeve extending rearwardly from the cone and enclosing the bearing sleeve, the apex of the cone forming with said sleeve a housing for the bearing sleeve the bearing members being each removable as a unit from the sleeve and from the shaft.

11. In a turbine, a shaft, a sleeve mounted for rotation on and enclosing one end of the shaft, bearings interposed between the sleeve and the shaft, a rotor plate, a sleeve projecting therefrom, and removably mounted on the bearing sleeve and enclosing it the bearing members being each removable as a unit from the sleeve and from the shaft.

Signed at Chicago, county of Cook and State of Illinois, this 25th day of March, 1926.

CHARLES W. DAKE.
